UNITED STATES PATENT OFFICE.

ALEXANDER SPITZER, OF BROOKLYN, NEW YORK.

TOY GAME DEVICE.

Application filed December 16, 1927. Serial No. 240,373.

This invention relates to a toy game device and its object is to provide a mechanism whereby skill, and accuracy of manipulation may be employed to strike and to drive a suspended ball into a position for scoring.

A further object is a means to bring characteristic symbols, or numerals into positions for scoring purposes.

These and other objects and features of the device will be set forth and fully described in the following specification and claims, and illustrated in the accompanying drawings, in which:

Fig. 1 is a perspective view showing the apparatus set up and in position for operation.

Fig. 2 is a vertical section on the line 2—2 of Figure 1.

Fig. 3 is a vertical section on the line 20 3—3 of Figure 1.

Fig. 4 is a modification illustrating the device in a form adapted for holding in the hand while in operation.

Referring first to Figure 1 of the drawings; the device comprises a back panel 5 which may be of wood or of any suitable material. A rotatable disk 6 is mounted on this panel, and near to its outer margin, the said disk is perforated by holes 7 placed at regular intervals and each having on the side nearest to the center of the disk, a groove or slot 8. The disk is divided into sectors 9 which may be of any distinctive colors if desired, and may be numbered 10, 20, 30 etc. as shown in the drawing, or may have other symbols for identification.

The disk may be spun around; and when it comes to rest, may be centered so that the lowest of the holes 7 is in alignment with 40 the hole 14 as seen in Figure 2 of the drawings.

A ball 15 is suspended on a cord 16 which is secured at the pivot 17; either by passing through the hollow center of same, as seen 45 in Figure 2, or in any suitable manner. This cord 16 is adjusted as to length so that the ball 15, when struck, will fly upward at the back of the panel, and if accurately hit will pass through the upper of the holes 7 and 50 rest there as seen at 18 in Figure 3; its course being indicated by the line 19 in Figure 1.

Referring now chiefly to Figure 2; a ball 21 is attached to an elastic cord 22 which is secured to the panel 5 at 23.

55 The game may be played in several ways,

but for illustration, it may be described as follows:

The disk 6 is spun around, and when it comes to rest, it may be adjusted as before stated so that the lowest hole will coincide with the hole 14 of the panel; the ball 15 hanging directly behind the same as seen in Figure 1. The ball 21 is then grasped by the player and drawn back in such a manner as to stretch the elastic cord 22 and is aimed with the intent to cause it to recoil and to accurately strike the ball 15 and cause it to fly up and to pass through the topmost hole. The player thus scores according to the numeral under the hole. If he fails to properly hit the ball 15, he loses his chance and does not score.

When not in use, the panel may be laid back in the box 30; it being hinged as seen in Figure 2 at 31. A forward brace 32 is secured to the bottom of the box when the panel is in an upright position.

The device constructed in the form shown in Figure 4 is adapted for holding in one hand by the handle 35, while the ball is manipulated by the other.

Having thus described my invention, what I claim as new and desire to secure by Letters Patent, is as follows:

1. In a toy device of the character described, a panel, an aperture therein, a pendent element attached to a flexible cord and adapted to be thereby suspended in a position behind and in alignment with the said aperture, another aperture above that first mentioned and so spaced with respect to the point of attachment of the said flexible cord, that the said pendent element may be thrown upward and brought into alignment therewith, an elastic cord secured at a point below the first mentioned aperture, and a striker element attached at the free end thereof and adapted to be drawn backward under tension of the said elastic cord, and upon release to strike the aforesaid pendent element.

2. In a toy device of the character described, a panel, a pendent element suspended at the back of the said panel on a flexible cord, and adapted to hang in a position in alignment with a hole in the said panel, another hole above that first mentioned and equidistant from the point of attachment of the said flexible cord to the supporting structure, an elastic cord secured at 110

a point adjacent to the first mentioned hole, and a striker element attached to the free end thereof and adapted to be drawn backward, and upon release to recoil and to strike the said pendent element and drive it upward in the restricted arc of its supporting cord.

3. In a toy device of the character described, an upright board element, a ball suspended on a flexible cord attached at the back of the said board element, and holes in the said board equidistant diametrically from the point of attachment of the said flexible cord and so placed that the said ball may hang opposite to one hole and upon being set in motion will fly in the arc of its cord radius into and through the diametrically opposed hole, and means to strike the said ball and to drive it in the arc as aforementioned.

4. In a toy device of the character described, an upright panel suitably supported a rotatable disk thereon mounted by means of a pivot element, a series of holes through the marginal area of the said disk and equidistant from the center thereof, holes in the panel structure equidistant from the pivot center and in the same radius as the holes in the aforesaid disk, a flexible cord secured

at the point of the pivot mounting and at the back of the said panel, and a pendent element attached to the said cord and adapted to hang opposite to a hole in the said panel, an elastic cord secured at a point adjacent to the said hole and a striker element attached at the free end of the said elastic cord.

5. In a toy device of the character described, a rotatable disk having marginal holes therein equidistant from the center and each within a distinctive sector of the said disk, the said disk pivotally mounted on a supporting panel, and an opening in the said panel permitting of free passage through any disk hole in alignment therewith, a flexibly suspended pendent element hung from the point of the pivot mounting and adapted to be swung from a position of alignment with one hole of the said disk, into and through another of the holes thereof, and means to strike the said pendent element and to swing it in the manner above described, substantially as shown and described.

Signed at New York in the county of New York and State of New York this 17th day of October, A. D. 1927.

ALEXANDER SPITZER.
